(57) **CLAIM**

The ornamental design for a vehicle windshield, as shown and described.

DESCRIPTION

FIG. 1 is a front elevational view of the vehicle windshield showing our design;

FIG. 2 is a detailed elevational view thereof;

FIG. 3 is a right side elevational view thereof;

FIG. 4 is a left side elevational view thereof;

FIG. 5 is a top-down plan view thereof;

FIG. 6 is bottom-up plan view thereof;

FIG. 7 is cross-sectional view taken along the lines 7-7 in FIG. 1;

FIG. 8 is right of center sectional view taken along the lines 8-8 in FIG. 1, a left of center sectional view is a mirror image of FIG. 8 and is not shown;

FIG. 9 is cross-sectional view taken along the lines 9-9 in FIG. 1;

FIG. 10 is cross-sectional view taken along the lines 10-10 in FIG. 1; and,

FIG. 11 is another detailed elevational view of the vehicle windshield (as viewed from the rear of the vehicle).
